(57) **CLAIM**

The ornamental design for camera clip, as shown and described.

DESCRIPTION

FIG. 1 is a perspective view of a camera clip showing our new design;

FIG. 2 is a front elevational view thereof;

FIG. 3 is a rear elevational view thereof;

FIG. 4 is a right elevational view thereof;

FIG. 5 is a left elevational view thereof;

FIG. 6 is a top plan view thereof; and,

FIG. 7 is a bottom plan view thereof.

The portions of the camera clip in broken lines are shown for illustrative purposes only and form no part of the claimed design.
